2 Claims

The present invention relates to dial illumination circuitry, and more particularly to dial illumination circuitry for use with VHF-UHF tuners.

The standardized use of both VHF and UHF tuners in presently produced television receivers has made it desirable to provide separate dial illumination for the particular tuner in operation. A common method of providing dial illumination for the tuners is the use of an incandescent bulb for each of the tuner dials with the associated switching circuitry. The requirement for additional switching circuitry for each of the tuning mechanisms, of course, increases the complexity and the cost of the television receiver. It would therefore be highly desirable to provide a dial illumination circuit utilizing existing switching circuitry while still providing the necessary dial illumination for both the UHF and VHF tuners.

It is, therefore, an object of the present invention to provide a new and improved dial illumination circuit.

It is a further object of the present invention to provide new and improved UHF-VHF dial illumination circuitry which utilizes existing switching circuitry of the tuners.

It is a further object of the present invention to provide a new and improved UHF-VHF dial illumination circuit which is readily adaptable for variations in the illumination function for either or both of the tuner dials.

Broadly, the present invention provides a dial illumination circuit for UHF and VHF tuners having a tuning switch for selecting one of the tuners to be operative wherein a VHF dial indicator light is illuminated when the switch is in the VHF position and a UHF dial indicator light is illuminated when the switch is in the UHF position.

These and other objects and advantages of the present invention will become more apparent when considered in view of the following specification and drawings, in which:

FIGURE 1 is a schematic diagram of one embodiment of the present invention; and

FIG. 2 is a schematic diagram of another embodiment of the present invention.

Referring to FIG. 1, one embodiment of the dial illumination circuit of the present invention for use in a television receiver is shown utilizing a VHF dial illuminator light L_v to illuminate a VHF dial D_v and a UHF dial illuminator light L_u to illuminate a UHF dial D_u . The dial illuminator lights L_v and L_u may each, for example, comprise a gas filled bulb such as a neon bulb. As is well known in the art, neon bulbs have a predetermined ionization potential which must be applied across the bulb to ionize gas within the bulb so as to emit light therefrom. The neon bulb will continue to emit light until the potential applied thereacross is reduced below an extinguishing potential. In a typical neon bulb, which could be used in the circuit of FIG. 1, the ionization potential would be, for example, approximately 90 volts, while the extinguishing voltage would be approximately 60 volts. In the example of FIG. 1, it is assumed that the illuminator lights L_v and L_u are neon bulbs having characteristics as described above.

In FIG. 1, the VHF tuner is shown schematically by a block V and UHF tuner is shown schematically by a

block U . The VHF dial D_v and the UHF dial D_u are mechanically coupled to the tuners V and U , respectively, to indicate the particular channel to which the receiver is tuned. The VHF tuner V has included therein a switch S_1 which is a normal component of the VHF-UHF tuner combination. The VHF tuner V is operative with the switch S_1 in its open position, as shown, and the UHF tuner U is out of the B_+ supply circuit. The closing of the switch S_1 causes the UHF tuner U to be placed into the B_+ supply circuit so that UHF television channels may be received. In a typical mechanical implementation of the tuner combination, the switch S_1 will be open for channel positions 2 through 13 and will be closed by the positioning of the VHF channel control knob at the space between channels 2 and 13.

For proper operation of the dial illumination circuit, when the switch S_1 is in its open VHF position, it is desired that the VHF illuminator bulb L_v be illuminated, and when the switch S_1 is closed that the UHF indicator bulb L_u be illuminated. These conditions are met in the circuit of FIG. 1 as may be seen from the following. Assume initially that the switch S_1 is in its open state as shown. Supply potential is supplied to the VHF tuner V from a source of B_+ potential, to be connected to a terminal T_1 , through a resistor R_1 . With supply potential supplied to the VHF tuner and the switch S_1 in its open state, the VHF tuner will be operative to receive television signals in the VHF frequency band. Connected between the B_+ terminal T_1 and ground is a voltage divider including the series connected resistors R_2 and R_3 . Connected across the resistor R_3 of the voltage divider is the VHF dial illuminator bulb L_v . Between the B_+ terminal T_1 and one end of the switch S_1 in the VHF tuner V , a voltage developing resistor R_4 is connected. The UHF dial illuminator bulb L_u is connected in series with a current limiting resistor R_5 , with the series combination of the UHF light L_u and the resistor R_5 being connected directly across the voltage developing resistor R_4 . The other end of the switch S_1 is connected to the UHF tuner U by a lead W_1 , with both the UHF tuner U and the VHF tuner V having ground connections.

The voltage developed across the VHF bulb L_v is determined by the voltage divider ratio:

$$\frac{R_3}{R_2+R_3}$$

times the B_+ potential. The resistive values of the resistors R_2 and R_3 are designed in view of the B_+ potential so that the ignition voltage of the light L_v is exceeded. The ignition value of L_v being exceeded, the bulb L_v will provide a light output which will illuminate the VHF tuner dial D_v of the television receiver. Since the voltage divider R_2 , R_3 is connected directly across the B_+ line, the light L_v will remain illuminated independently of the position of the switch S_1 . That is, if the switch S_1 is closed to its UHF position the same potential will be applied across the VHF illuminator bulb L_v so that the bulb will remain illuminated. In many instances it is desirable that the VHF indicator bulb be illuminated even when the UHF tuner is to be operative, since the VHF tuner bulb L_v may act as an indication that the UHF channel band is being utilized.

With the switch S_1 in its open position, no voltage is developed across the resistor R_4 connected across the UHF dial illuminator bulb L_u and the resistor R_5 , since an open circuit exists between the B_+ source and ground at the other end of the switch S_1 . Since no voltage is developed across the indicator light L_u with the switch S_1 open, the light L_u will be in its de-energized state and will emit no light therefrom. When, however, the switch S_1 is closed, a completed circuit is provided from the B_+ source through the resistor R_4 , the switch S_1 to the UHF

tuner to ground, so that a voltage drop is developed across the resistor R_4 and the series combination of the UHF illuminator bulb L_u and resistor R_5 . The resistive values of the resistors R_4 and R_5 are so selected that the ionizing potential of the neon bulb L_u is exceeded when the switch S_1 is placed in its closed position. The UHF dial illuminator light L_u remains ignited as long as the switch S_1 is closed. To extinguish the light L_u the switch S_1 is opened so that no voltage drop is developed across the resistor R_4 . The VHF illuminator bulb L_v , however, remains illuminated independently of the position of the switch S_1 , and stays in an ignited state until the $B+$ potential is removed from the circuit by, for example, turning off the television receiver. The resistor R_5 in series with the UHF dial light L_u acts to limit the current through the bulb L_u to maintain a reasonable lifetime for the bulb. Similarly, the voltage divider resistor R_2 acts to limit the current passing through the VHF dial illuminator bulb L_v .

FIG. 1 thus functions so that the VHF dial illuminator light L_v is illuminated with the switch in either its VHF or UHF tuner position, but with the UHF illuminator bulb L_u being illuminated only when the switch S_1 is in its closed UHF position.

FIG. 2 shows another embodiment of the present invention wherein the VHF dial illuminator bulb L_v is energized to provide light only when the switch S_1 is in its opened VHF position. The UHF illuminator bulb L_u functions as in FIG. 1 to provide light only when the switch S_1 is in its closed UHF position. These functions may be seen from the following. Assume initially that the switch S_1 is in its opened VHF position. A $B+$ potential will be supplied as in FIG. 1, from the terminal T_1 through the resistor R_1 to the VHF tuner V . A voltage developing resistor R_6 is connected between terminal T_1 and one end of a resistor R_7 . The UHF light L_u is connected in series with a current limiting resistor R_8 , with the series combination being connected across the voltage developing resistor R_6 . At the other end of the resistor R_7 , at a junction J_1 , a voltage divider including a resistor R_9 and a resistor R_{10} is connected between the junction J_1 and ground. The VHF dial illuminator bulb L_v is connected across the resistor R_{10} . The junction J_1 is connected to one end of the switch S_1 and the other end of the switch S_1 is connected through a lead W_1 to the UHF tuner U . Both tuners V and U have a ground connection to complete the circuit. Disposed to be illuminated by the VHF and UHF lights L_v and L_u , respectively, are the tuner dials, D_v and D_u , which are, respectively, mechanically coupled to the tuners V and U .

With the switch S_1 open as shown in FIG. 2, the voltage developed at the junction J_1 with respect to ground will be substantially high; that is, near the $B+$ potential. The resistive values of the resistors R_6 , R_7 , R_8 and R_{10} are so selected that with the switch S_1 open, a voltage sufficient to ignite the neon bulb L_v is developed across the resistor R_{10} . The VHF dial bulb L_v is thus ignited and continues to provide dial illumination as long as the switch S_1 remains in the open position.

The resistive value of the resistor R_6 is so selected in relation to the other circuit components that voltage developed thereacross with the switch S_1 in its open position is insufficient to ignite the UHF illuminator bulb L_u . In other words, the voltage developed across the VHF illuminator bulb L_v , which is proportional to the ratio

$$\frac{R_{10}}{R_6 + R_7 + R_8 + R_{10}}$$

is of sufficient magnitude to ignite the bulb L_v ; however, the voltage developed across the UHF illuminator bulb L_u , which is proportional to the ratio

$$\frac{R_6}{R_6 + R_7 + R_8 + R_{10}}$$

is insufficient to ignite the bulb L_u .

When UHF tuner operation is desired, the switch S_1 is closed. This supplies a potential to the UHF tuner from

the $B+$ source through the resistors R_6 , R_7 , the switch S_1 and the lead W_1 to the tuner U . At this time it is desired that the UHF illuminator bulb L_u be ignited and the VHF illuminator bulb be de-energized. This is accomplished since the closing of the switch S_1 provides a relatively low impedance path across the voltage divider including the resistors R_9 and R_{10} . Therefore, the voltage from the junction J_1 to ground drops, with the voltage provided across the VHF illuminator bulb L_v correspondingly dropping to a level below the extinguishing level of the bulb L_v . Since a relatively small voltage drop is provided between the junction J_1 and ground, a relatively high voltage drop is provided across the resistor R_6 . The circuit components are so designed that a sufficient voltage is developed across the UHF illuminator bulb L_u to cause this light to ignite. Thus, the VHF bulb L_v is de-energized since a relatively low voltage is provided thereacross with the switch S_1 being closed, and the UHF bulb L_u is energized by the high voltage developed across the resistor R_6 , which in turn provides a sufficient igniting voltage across the UHF bulb L_u .

The UHF light L_u is illuminated and the VHF light L_v is deenergized as long as the switch S_1 is maintained in its closed position. If VHF tuner operation is again desired, the switch S_1 is opened. This causes the voltage level at the junction J_1 to increase thereby increasing the potential across the VHF bulb L_v to above its ignition potential causing it to emit light. Accordingly, the potential across the resistor R_6 drops due to the increase of the potential at the junction point J_1 . The reduction of potential across the resistor R_6 causes the potential across the UHF bulb L_u to drop below its extinguishing level which causes the bulb L_u to extinguish. The reopening of the switch S_1 thus causes the VHF bulb L_v to be illuminated, while the UHF bulb L_u is extinguished.

In the physical implementation of the dial illumination circuits of FIGS. 1 and 2, the illuminator bulbs L_v and L_u would, of course, be disposed in such positions as to provide illumination to the respective VHF and UHF tuner dials D_v and D_u . It should also be noted that the switch S_1 being a normal component part of the VHF-UHF tuner combination effects the selective operation of the dial illuminator lights L_v and L_u without adding additional cost or complexity to the circuitry.

Although the present invention has been described with a certain degree of particularity, it should be understood that the present disclosure has been made only by way of example and that numerous changes in the details of construction and the combination and arrangement of parts and components may be resorted to without departing from the scope and the spirit of the present invention.

We claim as our invention:

1. A dial illumination circuit for VHF and UHF tuners having a tuner switch for selecting one of the tuners to be operative and to be supplied by a source of direct potential, said dial illumination circuit comprising:
  - a VHF voltage developing circuit connected across said source for developing a first VHF voltage;
  - a VHF dial illuminator light connected to said VHF voltage developing circuit and being responsive to said first VHF voltage to be illuminated thereby when said tuner switch is in a position to render said VHF tuner operative;
  - a UHF voltage developing circuit connected between said source and said tuner switch for developing a first UHF voltage when said tuner switch is in a position to render operative said UHF tuner; and
  - a UHF dial illuminator light connected to said UHF voltage developing circuit and being responsive to said first UHF voltage to be illuminated thereby only when said tuner switch is in a position to render said UHF tuner operative.
2. The dial illumination circuit of claim 1 wherein: said VHF voltage developing circuit developing said first VHF voltage when said tuner switch is in a position

tion to render said VHF tuner operative and developing a second VHF voltage when said tuner switch is in a position to render said UHF tuner operative; said first VHF voltage being of sufficient magnitude to illuminate said VHF dial illuminator light and said second VHF voltage being of insufficient magnitude to illuminate said VHF light; said UHF voltage developing circuit developing said first UHF voltage when said tuner switch is in a position to render said UHF tuner operative and developing a second UHF voltage when said tuner switch is in a position to render said VHF tuner operative; said first UHF voltage being of sufficient magnitude to illuminate said UHF dial illuminator light and said second UHF voltage being of insufficient magnitude to illuminate said UHF dial illuminator light.
